UNITED STATES PATENT OFFICE

2,557,330

CASING STRIPPING MACHINE SAFETY DEVICE

Jerome P. Wilger, Chicago, Ill., assignor to Swift & Company, Chicago, Ill., a corporation of Illinois

Application August 13, 1948, Serial No. 44,147

5 Claims. (Cl. 192—130)

1

This invention relates to a safety device for casing stripping machines in which opposed rotating rolls present an ever present danger to persons feeding material to the machine.

In the operation of casing stripping machines of the type herein referred to, a pair of superimposed parallel rolls are employed in casing stripping operations. A relatively narrow endless belt conveyor carries the casings into the space between the rolls, and casings are placed upon said conveyor manually. There is an ever present danger of the trapping of the hands or clothing of a person feeding the conveyor between the rolls, which could result in serious injury. The present invention proposes to provide a safety shield in front of the rolls and in close proximity to the path of movement of the conveyor belt and casings. The safety shield is preferably pivoted for swinging movement toward and from the rolls so that it will be engaged by the hands of an operator if the hands approach the rolls too closely. Pivotal movement of the shield in such a manner is caused to actuate a switch to immediately stop the motor employed in driving the rolls.

It is an object of this invention to provide a safety device of the nature set forth that is very simple in construction yet highly efficient and foolproof in operation.

It is further an object of this invention to provide a safety device of the type referred to that is extremely sensitive and yet of unusually rugged construction.

It is still a further object of this invention to provide such a safety device that is stable against accidental displacement.

Further objects and advantages will become apparent to those skilled in the art as the description proceeds with reference to the accompanying drawings, wherein:

Fig. 1 is a front elevational view of a casing stripping machine equipped with the safety device of the present invention and showing the driving means schematically;

Fig. 2 is an end view of the machine of Fig. 1 as viewed from the right end thereof; and

Fig. 3 is an isometric view of the safety shield of the present invention.

Casing stripping machines of the type upon which it is contemplated the present invention be applied generally comprise a supporting frame having end members 1 and 2 upon which a pair of parallel rolls 3 and 4 are rotatably mounted by means of shafts 6 and 7 journaled in the end members 1 and 2. Adjacent ends of the

2

shafts 6 and 7 carry meshing gears 8 and 9 of equal size affixed thereto and the shaft 7 additionally has a sprocket wheel 10 keyed or otherwise rigidly fixed thereon. The sprocket wheel 10 is driven by a sprocket chain 11 from a second sprocket wheel 12. The sprocket wheel 12 is mounted on the output shaft 13 of a worm type speed reducer 14 driven by a motor 15. By the arrangement described, it will be seen that the rolls 3 and 4 are caused to rotate in opposite directions at equal speeds whereby their opposed surfaces move in the same direction at substantially the same peripheral speed. The rolls 3 and 4 are sometimes covered by canvas or burlap covers 16 and 17. Each of the rolls 3 and 4 is likewise provided with a peripheral groove 18. A conveyor belt (not shown) extends generally horizontally into the groove 18 between the rolls, and casings are placed upon the conveyor belt by gravity or by an operator generally stationed immediately in front of the rolls. The endless conveyor belt is caused to move into the rolls to thereby feed the casings thereto. As is apparent, without the guard it would be possible for an employee attending the stripper machine to place his or her hands too near the rotating rolls 3 and 4 which could result in the hands being drawn into the rolls and seriously injured.

The safety device of the present invention comprises a forwardly extending bracket 20 on each of the end members of the machine and each bracket carries, adjacent its outermost end, a bushing or other suitable bearing means 21, preferably forwardly of the upper roll 3. A shaft 22 is rotatably mounted in the aligned bearings 21 and has rigidly attached thereto a shield indicated generally as 23. The shield comprises an upwardly and rearwardly extending portion 24, a downwardly extending portion or apron 25, and rearwardly extending end portions 26. The upper edge of the portion 24 and the lower edge of the portion 25 are preferably provided with "rolled" edges 27 and 28 to eliminate sharp or ragged portions. The downwardly extending portion 25 of the shield 23 extends to a point below the space between the rolls 3 and 4 and consequently below the path of travel of the endless belt referred to and the casing thereon. The portion 25 of the shield is therefore provided with a cutout portion 29 of such configuration and extent as to clear the endless conveyor belt and the casings thereon and allow the latter to move into the rolls without interference from the shield.

Adjacent one end of the shaft 22 and preferably between an end portion 26 and the adjacent bearing 21, a bracket 30 is rigidly mounted. The bracket 30 carries a switch mechanism 31, to be described later. At the end of the shaft 22 opposite from the switch 31 the said shaft is provided with a collar 32 rigidly affixed thereon. The collar 32 is provided with an inwardly extending notch 33 at its periphery, said notch having a generally radial shoulder portion 34. A pawl or detent 35 is pivoted to the end member 2, as at 36, and is of such length that its free end may be moved into position to engage the notch 33 in the collar 32. An end surface of the pawl 35 abuts the shoulder 34 of the collar 32 and acts as a stop to prevent rotation of the shaft 22 in a clockwise direction as seen in Fig. 2, beyond the position where the shoulder 34 is so engaged. The shaft 22 and shield 23 may, however, rotate freely in the opposite direction.

Adjacent the collar 32 shaft 22 is provided with a sleeve 37 having a radial arm 38 extending therefrom. A counterweight 39 is longitudinally adjustable along the arm 38 and may be fixed in adjusted position by means of a set screw or the like. The sleeve 37 may also be angularly adjusted about the shaft 22 and may be fixed in adjusted position by means of a set screw or the like. The counterweight 39 and stop means 34-35 mutually act to urge the shaft 22 and the shields 23 to a fixed position in which the switch 31, previously referred to, is in a predetermined position. It will be seen that by the arrangement just described vibrations in the vicinity of the machine or accidental displacement of the shield 23 through small angles will not result in actuation of switch 31 and, yet, the said shield is free to be displaced by a sufficient force to effect stopping of the machine.

The switch 31 is preferably of a mercury type wherein tilting of the switch beyond a normal position causes a pool of mercury to flow therein and make or break an electrical circuit between spaced contacts. The switch 31 is arranged in an electrical circuit including the conductors indicated generally at 40. The conductors 40 are connected to a plugging switch 41 which in turn is connected to an extension of the high speed shaft 42 of the speed reducing unit 14. The plugging switch 41 is of a known type and need not be described in detail. When the switch 31 is tilted beyond the positions shown in the drawings the circuit therethrough will be broken and the plugging switch 41 will thereby become conditioned to effect breaking of the power circuit to the motor 15 and a reversal of the current in the motor until the motor is instantaneously stopped.

If desired the machine described may be provided with means (not shown) to effect quick and easy lifting of the top roll 3 in the event an operator becomes caught between the said rolls. Such means could readily be made automatically operable upon actuation of the shield 23 and/or the switch 31.

Clearly the safety device described is not limited to use with the specific machine shown but may be readily adapted for use with any machine in which material or work pieces are manually fed to moving parts.

It will be apparent to those skilled in the art that various changes and modifications may be made without departing from the spirit of the invention. It is intended that the invention be limited only by the scope of the appended claims.

I claim:

1. A casing stripping machine comprising a frame, a pair of elongated superposed rolls journaled on said frame; means for driving said rolls to receive and squeeze material therebetween; a shield pivoted to said frame on an axis generally parallel to the axes of said rolls, said axes being spaced forwardly of the upper of said rolls, said shield being of substantially the same length as said rolls and comprising a portion extending downwardly from said axis having a lowermost edge forwardly of and spaced from the lower of said rolls, a portion extending upwardly and rearwardly from said axis, and end portions extending transversely to said axis and rearwardly toward the ends of said rolls, the downwardly extending portion of said shield having a cut-away portion through which material may be conveyed to a position between said rolls; a switch for controlling said driving means, shoulder means connected to said shield for movement therewith; stop means on said frame cooperating with said shoulder means to prevent movement of the upwardly portion of said shield towards said rolls while permitting pivotal movement of the shield in the reverse direction, substantially all of said shield being between said axis and said rolls whereby the weight of said shield tends to hold the shoulder means in engagement with said stop means; and means whereby pivotal movement of said shield in said reverse direction will actuate said switch to stop said power means.

2. In a casing stripping machine the combination of a frame; a pair of superposed stripping rolls; electrically operated power means to drive said rolls; and a safety device to prevent an operator from accidentally getting an appendage caught between the rolls, said safety device including a pivotally mounted shield positioned about the space in front of the line of contact between the rolls and obstructing substantially all access to said line from the front, sides and top thereof, means to limit the pivotal movement of the upper portion of said shield towards said rolls, and electric switch means electrically connected to said power means to effect stopping of said rolls in response to a pivotal movement of said shield in the opposite direction.

3. In a casing stripping machine the combination of a vertical frame; a pair of superposed stripping rolls journaled in said frame in contact with each other; electrically operated power means to drive said rolls; and a safety device to prevent an operator from accidentally getting an appendage caught between the rolls, said safety device including a pair of brackets projecting to one side of said frame and positioned to either end of said rolls, a shield between said brackets and pivotally mounted therefrom along a line spaced from said side of said frame and rolls and above the line of contact between the rolls, said shield having an apron extending downwardly from said pivotal line to below said line of contact, said shield also having an upper inclosure member extending toward the upper of said superposed rolls from said pivotal line, stop means to limit the pivotal movement of said upper member of the shield toward said rolls, and electrical switch means electrically connected to said power means to effect stopping of said rolls in response to a pivotal movement of said shield in the opposite direction.

4. A safety device for a casing stripping machine comprising a frame, a pair of elongated superposed rolls journaled on said frame, and

means for driving said rolls to receive and squeeze material therebetween, said device including a shield pivoted to said frame on an axis generally parallel to the axes of said rolls, said axis being spaced forwardly of the upper of said rolls, said shield being of substantially the same length as said rolls and comprising a portion extending downwardly from said axis having a lowermost edge forwardly of and spaced from the lower of said rolls, a portion extending upwardly and rearwardly from said axis, and end portions extending transversely to said axis and rearwardly toward the ends of said rolls, the downwardly extending portion of said shield having a cut-away portion through which material may be 15 conveyed to a position between said rolls, a switch for controlling said driving means, shoulder means connected to said shield for movement therewith, stop means on said frame connecting with said shoulder means to prevent movement of the upwardly portion of said shield towards said rolls while permitting pivotal movement of the shield in the reverse direction, substantially all of said shield being between said axis and said rolls whereby the weight of said shield tends to hold the shoulder means in engagement with said stop means, and means whereby pivotal movement of said shield in said reverse direction will actuate said switch to stop said power means.

5. A safety device to prevent an operator from accidentally getting an appendage caught be-

tween the rolls of a casing stripping machine having a frame, a pair of superposed stripping rolls and electrically-operated power means to drive said rolls, said device including a pivotally mounted shield positioned about the space in front of the line of contact between the rolls and obstructing substantially all access to said line from the front, sides and top thereof, means to limit the pivotal movement of the upper portion 10 of said shield towards said rolls, and electric switch means electrically connected to said power means to effect stopping of said rolls in response to a pivotal movement of said shield in the opposite direction.
